UNITED STATES PATENT OFFICE

2,362,955

HEAT EXCHANGE UNIT

John D. Cantwell, Detroit, Mich., assignor to The
Trane Company, La Crosse, Wis.

Application July 10, 1941, Serial No. 401,814

2 Claims. (Cl. 98—40)

The object of my invention is to provide a heat exchange unit with means for adjustably controlling the direction of the air passed through the unit in accordance with the various heights of the room in which the unit is placed, with particular reference to a unit forcing the air downward from the ceiling.

Another object of my invention is to provide adjustable means whereby the air may be spread either laterally or directed vertically downward.

The foregoing and many other specific features of my invention are set forth in the following specification, where I describe what I consider the preferred embodiments of my invention. They are illustrated in the accompanying drawings wherein—

Figure 1 is a vertical front elevation of the unit showing the adjustable vanes forming a frustum of a cone.

Figure 2 is a plan view taken on the lines 2—2 of Figure 1.

Figure 3 is a front elevation of the unit.

Figure 4 is a plan view taken on the lines 4—4 of Figure 3.

Referring to the aforesaid figures, 10 is a circular heat exchanger comprising fins 11 mounted on heat tubes 12, and is supported between an upper casing 13 and a lower casing 14. A motor 15 is mounted on the casing 13 and actuates a fan 16 which draws air through the inlet 17, through the heat exchanger and forces the air out preferably downward through the outlet 18 in the lower casing 14. Below the fan and in the path of the emitted air are a series of vanes 20 supported and positioned by rods 19 which are attached at one end to the lower casing 14 by nuts 21 and at the other end to a circular web 22 by nuts 23. Each vane 20 corresponds to a segment of a frustum. If the vane is curved, it would correspond to the segment of a frustum of a cone and if flat to the frustum of a pyramid. When all the vanes are placed together with edges proximate the edge of the nearest vane, the form approximates that of a frustum. The center of each vane is pivotally attached to circular web 22 as at the point 24 and to an interior circular web 25 at the point 26 so that the vane 20 may pivot on an axis formed by the line from 24 to 26. The circular web 25 also forms a circular opening which causes an aspirating effect varying with the position of the vanes. When

the deflector is in the form of a frustum of a cone, air moving over the surface of the cone will induce secondary air upward through the cone, which is designated as an aspirating effect, and which diminishes as the vanes are moved out of the form of the frustum. When the vanes 20 are in a common plane, they form with each other a frustum of a cone which has the effect of directing the air laterally, which is particularly useful when the device is installed in rooms with low ceiling heights and a lateral flow of air is desired to prevent drafts. However, in rooms with a high ceiling, it is oftentimes desirable to vary the amount of lateral deflection or to have no deflection, in which case the vanes may be pivoted individually on their axis so as to vary the amount of deflection or as to allow substantially no interference with the flow of air from the fan 16 without affecting the fan performance.

I claim:

1. An outlet for unit heaters comprising an inner hollow web and a larger outer web, movable vanes attached to said webs, said vanes in a closed position forming the surface plane of a frustum of a hollow cone, said vanes being pivotally attached to said webs as to allow movement of said vanes out of said plane, the said inner web being centrally positioned in the path of the discharge air of the unit heater and spaced closer to the unit heater than the said outer web, rods supporting and spacing the outer web from the unit heater.

2. An outlet for unit heaters comprising an inner hollow web and a larger outer web, movable vanes attached to said webs, said vanes in a closed position forming the surface plane of a frustum of a hollow cone, said vanes being pivotally attached to said webs as to allow movement of said vanes out of said plane, the said inner web being centrally positioned in the path of the discharge air of the unit heater and spaced closer to the unit heater than the said outer web, rods supporting and spacing the outer web from the unit heater, whereby secondary air will be induced upward through said inner web when said vanes are in a closed position and whereby the volume of said secondary air will be varied when the said vanes are moved out of said plane.

JOHN D. CANTWELL.
